DESIGN FOR A DISPLAY COUNTER

Bertrand R. Walsh, Forest Hills, N. Y.

Application December 10, 1947, Serial No. 143,087

Term of patent 14 years

(Cl. D80—2)

To all whom it may concern:

Be it known that I, Bertrand R. Walsh, a citizen of the United States of America, residing at Forest Hills, in the county of Queens and State of New York, have invented a new, original, and ornamental Design for Display Counter, of which the following is a specification, reference being had to the accompanying drawing, forming part thereof.

Fig. 1 is a perspective front view of the display counter, embodying my new design; and

Fig. 2 is a sectional view taken on line 2—2 of Fig. 1.

I claim:

The ornamental design for a display counter, substantially as shown.

BERTRAND R. WALSH.
